UNITED STATES PATENT OFFICE.

CHESTER E. WARNER AND ARTHUR N. NILSON, OF CHICAGO, ILLINOIS, ASSIGNEES
TO BENJAMIN ELECTRIC MANUFACTURING COMPANY, OF CHICAGO, ILLINOIS, A
CORPORATION OF ILLINOIS.

CONDENSER STRUCTURE.

Application filed October 8, 1927. Serial No. 224,824.

Our invention relates to a condenser structure.

One of the objects of our invention is to provide an improved condenser structure in which the range of movement of the movable condenser element for a given movement of the manually operable member may be varied.

A further object of our invention is to provide an improved condenser structure in which a selective variable speed transmission is provided for varying the capacity curve of the condenser.

A further object of our invention is to provide a gang condenser structure having a simple adjustment whereby the capacity curves of the variable condensers may be adjusted after the radio receiving set is completely connected up, so as to give the desired characteristics to the various circuits at all settings of the common manual controller.

Further objects will appear from the description and claims.

Generic claims on the construction disclosed in this application are presented in our co-pending application Serial No. 212,964, filed August 15, 1927.

In the drawings, in which an embodiment of our invention is shown,

Fig. 1 is a front view of a panel of a radio receiving set with which our improved condenser structure may be used;

Fig. 2 is a front view of the metal supporting plate or chassis with the parts supported thereby;

Fig. 3 is a rear view of the chassis and parts supported thereby;

Fig. 4 is a section on the line 4—4 of Fig. 1; and

Fig. 5 is a section on the line 5—5 of Fig. 4.

Referring to the drawings in detail, the construction shown comprises a plurality of similar condenser units 1, two being shown, a metal plate or chassis 2 on which these condenser units are mounted, an insulating panel 3 in front of the metal plate, a manually operable knob 4 for simultaneously actuating both of the condenser units, an indicating dial 5, and transmission from the knobs to the individual condensers.

This transmission includes a shaft 6 on which the knob 4 is secured, a pinion 7 secured to this shaft, a universal bar 8 having a rack

portion 9 meshing with this pinion, and a selective variable speed transmission between this universal bar and the movable element of each of the condenser units.

These selective variable speed transmissions for the condenser units are similar and each comprises a two-armed rock member 10 pivotally mounted at 11 on a bracket 12 secured to the universal bar 8 a follower 13 pivotally secured to one arm of this rock member, an adjustable guide or track 14 in which this follower slides, a pair of pulleys 15 rotatably mounted on the universal bar, and a flexible belt or cable 16 having ends secured to the two ends of the two-armed rock member 10, respectively, and passing over the two pulleys 15, and secured to a rotatable pulley member 17 secured to the oscillatable shaft 18 on which the oscillatable condenser plates 19 are mounted.

The condensers 1, knob 4, and the entire transmission between the knobs and condensers, may be mounted on the metal supporting plate or chassis 2. The shaft 6 on which the manually operable knob and the pinion are mounted, may itself be rotatably mounted in a bearing bracket or sleeve 20 secured to the rear of the chassis by means of rivet members 21.

The indicating dial 5 may be mounted on a sleeve member 22 which in turn is rotatably mounted on the bearing sleeve 20. The sleeve 22 on which the dial is mounted may have a pulley portion 23 formed integral therewith, this pulley having secured thereto a flexible belt or cable member 24 which passes therearound, and the ends of which are secured to brackets 25 mounted on the universal bar 8. With this construction when a knob is rotated the pinion will cause the universal bar to be shifted longitudinally and the dial to be rotated by means of the cable and pulley transmission.

A suitable stationary index may be provided for cooperating with the dial, a portion of the dial and this stationary index being visible through a suitable window 26 provided in the front panel.

In order to take up slack on the transmission cable one end may be provided with a suitable adjustment comprising a screw 27 to which the end of the cable is secured, which screw extends through a laterally extending

lug 28 on the two-armed rock member 10 and is provided with an adjusting thumb nut 29 which bears on the upper face of the lug 28, so that by turning this thumb nut the cable 5 may be tightened or slackened.

Each end of the track or guide 14 in which the follower 13 slides is adjustable independently of the other end by means of screws 30, each having threaded engagement 10 with a flange 31 on the chassis plate 2. The points of these screws bear on the upper side of the adjustable track 14, a leaf spring 32 is provided for holding the track up against the point of the screws. The screws, the 15 adjustment of which determines the position of the track are so positioned that when the corresponding condenser is in one of its extreme positions a slide will be directly under one of the screws, and so that when the 20 condenser is in its other extreme position the slide will be directly under the other screw. By reason of this positioning of the screws one of the extreme positions of the condenser may be varied without varying the other extreme 25 position of the condenser to any appreciable extent. From this construction it results that one end of the capacity curve of the condenser may be varied without appreciably affecting the other end of the capacity 30 curve, and vice versa.

The track is guided in its adjusting movement by means of a pair of screws 33 extending through vertical slots 34 in the chassis plate 2 and threaded into the guide 14. When 35 the track has been adjusted to the desired position it may be firmly held there by taking up these guide screws 33.

By means of this independent adjustment for the two condensers either one may be 40 made to have its initial position anything desired within the limits of the adjusting means, and also to have its final position anything desired within the limits of the adjusting means, and because of the fact, as previously 45 pointed out, that in the initial position of the condenser the slide is directly under one adjusting screw and in the final position the slide is directly under the other adjusting screw. The initial position of the 50 condenser may be changed without changing the final position of the condenser and vice versa.

By means of this construction a receiving set may be assembled without taking pains 55 in matching condensers and coils, and after the set is all complete the condensers may be adjusted so as to give the desired characteristics to the various circuits at all settings of the common manual controller.

60 While we have described but one embodiment of our invention, it is obvious that many modifications therein may occur to those skilled in the art, and we desire, therefore, that our invention be limited only by the

scope of the appended claims and by the prior art.

We claim:

1. A condenser construction comprising a movable condenser element, a manually-operable member for actuating the movable condenser element, and means for varying the capacity curve for the condenser comprising a selective variable speed transmission between the manually operable member and the movable condenser element, said variable speed transmission comprising a member 70 movable back and forth and actuated by said manually operable member, an arm pivotally mounted on said movable member, an adjustable guide for controlling the movement of said arm, and transmission between said arm and the movable condenser element, said last transmission comprising a belt member and a rotatable member actuated by said belt member. 75

2. A condenser construction comprising a movable condenser element, a manually-operable member for actuating the movable condenser element, and means for varying the capacity curve for the condenser comprising 90 a selective variable speed transmission between the manually operable member and the movable condenser element, said variable speed transmission comprising a member movable back and forth and actuated by said 95 manually operable member, a two-armed rock member pivotally mounted on said movable member, an adjustable guide for controlling the movement of said rock member, and transmission from said two-armed member to said movable condenser element comprising belt means secured to the two arms of said rock member respectively, and a rotatable member actuated by said belt means. 100

3. A gang condenser construction comprising a plurality of condensers, each having a movable condenser element, a common manually-operable member for actuating all of said movable condenser elements and means for varying the capacity curve of one of said 105 condensers comprising a selective variable speed transmission between said manually-operable member and a movable element of said condenser, said variable speed transmission comprising a member movable back and forth and actuated by said operable member, an arm pivotally mounted on said movable member, an adjustable guide for controlling the movement of said arm, and transmission between said arm and the movable condenser element, said last transmission comprising a belt member and a rotatable member actuated by said belt member. 115

In witness whereof, we have hereunto subscribed our names.

CHESTER E. WARNER.
ARTHUR N. NILSON.
